GARMENT PRESS

William Strobridge, Syracuse, N. Y., assignor to
 United States Hoffman Machinery Corporation,
 New York, N. Y., a corporation of Delaware

Application April 1, 1940, Serial No. 327,290

2 Claims. (Cl. 38—36)

This invention relates to garment presses, and particularly to garment presses of the toggle-operated type.

The usual press of this character comprises a support on which the buck is mounted and a lever pivoted to the support and carrying the press head which cooperates with the buck. A duplex toggle mechanism is used comprising a so-called "secondary toggle" which reacts between the support and the press lever, and a primary toggle made up of a manually operated lever fulcrumed on the support and a link which connects this lever with one component of the secondary toggle. Neither toggle straightens completely, but they approach so closely to a straightened condition that the multiplication of force from the pedal to the press head is very great. This implies that for a large pedal movement in the final motion of the press, there is a very small motion of the press head.

Hence, it is possible to use an ordinary bumper or cushion to limit the closing motion of the press linkage and still secure sound operation.

However, near the open position of the press, the force ratio between the pedal and the press lever is very greatly diminished, with the result that the linkage has an accelerated motion as the press opens. The arrest of the linkage at the limit of opening motion has always been a problem, both from the standpoint of shock and noise. The problem has been to produce a buffer which could be constructed inexpensively and which would have sufficient range of motion during the buffering action and would exert sufficient buffering force to secure a silent and comparatively shock-free arrest of the opening movement of the linkage. It may be remarked that the press lever, with its counterweight, is quite heavy and that accumulated momentum which must be absorbed by the buffer is considerable.

The present invention provides a buffer which reacts between the two links of the secondary toggle, and has remarkably effective characteristics in buffering the opening movement of the press. The structure is simple and operates silently and effectively. The reason for this is that during the opening movement of the press, the buffer reacting between the two link elements of the secondary toggle not only checks the motion of these toggle links but also imparts a check resistance directly to the press lever which carries the press head and the counterweight.

In order to illustrate the best embodiment known to me, the invention will now be described

as embodied in a commercial press of known form.

In the accompanying drawings:

Figure 1 is a view chiefly in side elevation of the press, certain parts of the support being broken away to disclose the linkage. The press is shown closed and latched.

Figure 2 is a similar view showing the open position of the press.

Figure 3 is an axial section on an enlarged scale of the buffering components shown in Figures 1 and 2.

The main frame or support of the press is generally indicated by the reference numeral 11. This has an upstanding member 12 on which the so-called "buck" or lower press element 13 is mounted. The base 11 has at its rear an upward extension 14 on which the press lever 15 is pivoted at 16. The press lever carries at its 10 forward end a press head 17 arranged to coact with the buck 13 and is provided at its rear end with a counterweight 18. A coiled tension spring 19 reacts between the base 11 and the lever 15 in such a way as to urge the press open, that is, to lift the head 17 away from the buck 13.

Extending forward from the forward end of the lever 15 is a handle 21 which the operator may grasp to draw the head 17 downward against the buck 13. However, when pressure is to be 20 developed, the press may be closed and subjected to pressure by depressing the main foot pedal 22 which operates through a toggle linkage, now to be described.

The toggle is of the duplex type and comprises 25 a secondary toggle made up of a link 23 and a link 24 hinged together at 25. The lower link 24 is pivoted to the frame 11 at 26 and the upper end is pivoted at 27 to the horizontal arm of a bell crank 28 which is pivoted at 29 to the lever 15. The purpose of using the bell crank is to 30 adjust the position of the pivot 27 relatively to the lever 15 and thus adjust the pressure developed between the head 17 and the buck 13 by the closing of the press. To effect this adjustment, a tension rod 31 is threaded into clevis 32 which is pinned at 33 to the vertical arm of the bell crank 28 and is rotatably mounted at 34 in a cross member 35 which extends between the two arms of the press lever 15, the forward end 35 of the lever 15 being bifurcated as is usual in the press art. The adjustment is effected by turning a hand wheel 36 which is pinned to the rod 31.

The primary toggle comprises a so-called 40 "front lever" 31 which is fulcrumed at 38 on the

frame 11 and which is connected by a link 39 with the main foot pedal 22 already described. This pedal is fulcrumed at the rear of the press at 26 concentrically with the lower link 24. The rear end of the front lever 37 is connected with the lower toggle link 24 by a short toggle link 41 which is hinged to the rear end of lever 37 at 42 and which is pinned to the lower secondary toggle link 24 at 43. When the press is open, the parts assume the position shown in Figure 2.

Depression of the pedal 22 draws the linkage to the position shown in Figure 1 in which the closing motion of the linkage is arrested by a resilient bumper 44 which is threaded in a boss 45 carried by the link 41. The purpose of the threaded mounting is to permit adjustment of the bumper 44, said adjustment (when made) being fixed by the lock nut 46. The bumper 44 engages the upper end of toggle link 24 approximately opposite the pivot of the hinge 25. It will be observed that the centers of the hinge connections 26, 25, 27 do not quite reach alignment, and the same is true of 38, 42 and 43, but these parts are moved so nearly into alignment that at the time the bumper 44 engages the upper end of the link 24, the parts are moving quite slowly.

The press is held in its closed position of Figure 1 by a latch which is pivoted at 47 on the link 24 and has a latch nose 48 which enters beneath a roller keeper 49 on the link 41. The latch is urged in engaging direction by a coil compression spring 51 and carries a tail 52 by which it may be disengaged in closed position of the press. To accelerate opening movement of the links 23, 24, a tension spring 53 is connected to react between a portion of the base 11 and the link 24. The latch 48 may be disengaged, either by a foot pedal or by a finger-tip release mechanism mounted adjacent the handle 21, the latter being used also during the so-called "pattting" operation in which the head is patted against the buck without permitting the press to lock.

The latch releasing mechanism comprises a trigger 54 pivoted at 55 on a portion of the frame 11. The trigger 54 is so located that in the closed position of the press (Figure 1) it overlies the tail 52 and will depress that tail, releasing the latch, if the trigger 54 is rocked in a clock-wise direction.

To rock the trigger 54, there is provided an arm 56 which is rigidly connected to the trigger 54 and which is connected by a link 57 with a rearward arm 58 of a latch foot lever 59. This is fulcrumed at 61 in the frame 11. It is urged in a clock-wise direction by a coil compression spring 62, the limit of clock-wise motion being adjustably determined by a screw stop 63. The arm 56 is also connected by a link 64, bell crank 65 and link 66 with a finger lever 67 which is fulcrumed at 68 on the press lever 15 and carries a finger piece 69 which may be depressed to release the latch 48 and hold it released so long as the finger piece 69 is held depressed and the press is in approximately its closed position.

To cushion the opening movement of the press lever and the toggle linkage, an hydraulic buffer generally indicated by the numeral 71 applied to its housing, is bolted to the rear face of the link 24 near the upper end thereof. The movable buffering element is the head 72 on a plunger mounted in the housing 71 and constructed as hereinafter described.

A boss 73 is formed on the rear face of the upper link 23 in position to engage the head 72 and force it inward relatively to the housing 71 in the last portion of the opening movement of the press (see Figure 2).

Referring now to Figure 3, the housing 71 is formed internally with a cylindrical guide 74 beneath which is a chamber 75 and to one side of which is a reservoir chamber 76. A leak port 10 77 leads from the side of the cylindrical guide 74 to the chamber 76 and the capacity of this port is adjustable by turning the valve stem 78 so that the conical end of the valve stem enters more or less into the port 77 and consequently throttles it to any desirable degree.

The lower end of chamber 75 is closed by screw plug 79 which is sealed by a gasket as shown, and which serves as a seat for a coil compression spring 81. The upper end of the housing 71 forms a cylindrical guide 82 which is co-axial with the cylindrical guide 74, and which serves to guide enlargements 72 and 84 on the stem 83. A stop screw 85 is provided to limit outward motion of the stem 83 under the urge of the spring 81 which reacts against the spring seat 86 formed at the lower end of the stem 83. This spring seat 86 also limits the downward motion of an annular or centrally ported piston 87 which has lost motion between itself and a valve head 30 88 formed on the stem 83.

The valve head 88 normally stands above the upper end of the piston 87 but initial inward motion of the stem 83 causes the valve head 88 to seal against the upper face of piston 87 after 35 which they move downward together. The effect is to inhibit flow through the central port in the piston and thus develop pressure in space 75 beneath the piston. This pressure is relieved by throttling flow through port 77. Piston 87, however, is so dimensioned that very shortly after it starts to move downward, it commences to throttle port 77 in addition to the valve 78 with the result that a sharply increased resistance is offered to downward motion of the stem 83.

45 Thus, when boss 73 starts to force head 72 downward the first effect is to close valve head 88 against valve 87, after which the parts move together, first against the throttling resistance offered by port 77, and then against the rising 50 resistance imposed by progressive reduction of area of the port 77 because the port is overtraveled by the piston 87. This gives a desirable characteristic to the check because the initial resistance is offered by the spring, then after 55 short motion, a definite hydraulic resistance is imposed, and on further motion, the hydraulic resistance builds up very rapidly until it is almost a positive arrest occasioned by the substantial closure of the port 77.

60 A device of this type can be made to operate very effectively and silently, and since it checks rather rapid relative motion of the links 23 and 24, and these links react between the base 11 and the head lever 15, the buffering force is applied where it is most effective to arrest motion without serious jar or vibration. It will be observed that no rebound tendency can be imparted by the check because initial downward motion of the plunger 72 dissipates pressure beneath the plunger so that the only reaction that could be offered is the relatively low force exerted by the spring 81.

70 While the press has been described in considerable detail, it will be appreciated that the invention is applicable to presses of specifically

different forms and no necessary limitation in this regard is implied.

What I claim is:

1. In a garment press, the combination of a support; a press lever fulcrumed on a fixed portion of said support; cooperating pressing members carried by said support and lever; a toggle for bringing said pressing members into and out of pressing relation, said toggle comprising a pair of links hinged together and interposed between said support and lever; means for straightening the toggle; yielding means reacting upon said toggle to open the press; a buffer of the hydraulic type including a yielding plunger mounted on one of said links; and means on the other of said links arranged to displace said plunger only near the limit of opening movement of the toggle.
2. In a garment press, the combination of a support; a press lever fulcrumed on a fixed portion of said support; cooperating pressing members carried by said support and lever; a toggle

for bringing said pressing members into and out of pressing relation, said toggle comprising a pair of links hinged together and interposed between said support and lever; means for straightening the toggle; yielding means reacting upon said toggle to open the press; a liquid charged cylinder structure mounted on one of said links; piston means guided in said cylinder and operable to displace liquid therefrom upon inward motion of the piston, said piston including a plunger projecting from said cylinder structure; a spring urging said piston and plunger outward; valve means associated with said piston and adapted to delay inward motion of the piston by retarding liquid displacement but permitting rapid return flow; and means on the other of said links positioned to displace said plunger inward only near the limit of opening movement of the toggle whereby arrest of the opening movement of the press is cushioned.

WILLIAM STROBRIDGE.
